UNITED STATES PATENT OFFICE.

JOHN B. BARNETT, OF NORWOOD STATION, PENNSYLVANIA, ASSIGNOR TO PHILADELPHIA ELECTRO PRINTING PRESS & MFG. CO., OF NORWOOD STATION, PENNSYLVANIA, A CORPORATION OF DELAWARE.

PRINTING PRESS.

Application filed August 15, 1922. Serial No. 581,962.

To all whom it may concern:

Be it known that JOHN B. BARNETT, a citizen of the United States, residing at Norwood Station, in the county of Delaware and State of Pennsylvania, has invented certain new and useful Improvements in Printing Presses, of which the following is a specification.

This invention relates to printing presses and has special reference to an electrical operating printing press.

One important object of the invention is to improve the general construction of devices of this character.

15 A second important object of the invention is to provide an improved electrical operated printing press of the flat platen type, such as is used for small jobs, engravers' work, and the like.

20 A third important object of the invention is to provide an improved automatically operated electric printing press wherein the introduction of a sheet of paper serves to close a circuit and thereby actuate the press.

25 A fourth important object of the invention is to provide an improved electrical operated printing press wherein a closed circuit which brings the platen into printing position is automatically opened immediately a printing is completed.

With the above and other objects in view as will be hereinafter apparent, the invention consists in general of parts hereinafter fully described, illustrated in the accompanying drawings and specifically claimed.

In the accompanying drawings like characters of reference indicate like parts in the several views, and:—

Figure 1 is a side elevation partly in section of the improved press.

Figure 2 is a transverse section on the line 2—2 of Figure 1.

Figure 3 is an enlarged detail view of automatic circuit closing and opening device.

Figure 4 is a detail showing the modified arrangement of electrical operating means.

In the embodiment of the invention herein disclosed the press is provided with a bed or base 10 for the reception of the form 11 carrying the type 12. Extending upward from the ends of the bed or base are standards 13 which are connected at their top by a transverse member 14. Through this

transverse member extends a shaft or plunger 15 which forms the core of a solenoid 16 supported on the transverse member. On the lower end of this plunger, or core, is mounted the platen 17 which has at its ends guide yokes 18 embracing and guided by the uprights or standards 13. This platen is normally held in its raised position by springs 19, the lower end of these springs being secured to the platen and the upper ends to the transverse member 14. At the rear of the base there is provided a notch 20 wherein is mounted an insulating block 21 carrying a contact 22 connected to a battery 23 or other source of electric energy by a wire 24. Also across this notch extends a pin 25 whereon is mounted an arm 26 carrying the contact 27 insulated from the arm and connected by a wire 28 with the solenoid 16. Also the battery 23 is connected by a wire 29 with said solenoid. Ordinarily the contacts 22 and 27 are held apart by a spring 30 which urges the lower end of the arm or lever 26 away from the contact 22. The upper end of this arm or lever projects above the type as can be readily seen in Figures 2 and 3 and in this position is engageable by the sheet of paper P as the latter is inserted. The spring 30 is very light so that the engagement by the paper forces the contact 27 with the contact 22 and thus closes a circuit through the solenoid 16. The closing of this circuit causes depression of the platen 17 and on the edge of this platen there is provided a notch or slot 31 so that the upper end of the lever 26 passes up thereto. Also there is mounted on the platen a cam member 32 which, when the platen is in its lowermost position engages the upper end of the lever 26 and draws it inward so that the contact 27 is moved away from the contact 22. Thus, the circuit is broken through the solenoid and springs 19 return the platen to its former position.

In the form of the invention shown in Figure 4 the solenoid 16 is replaced by series of electromagnets 33 positioned below the base which thus becomes an electromagnet pole and serves to attract the platen 17 when energized, the latter being made of iron.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention what is claimed as new, is:—

1. In a printing press, a base, standards extending up from said base, a transverse member connecting the upper ends of said standards, a plunger slidable through said transverse member and constituting a solenoid core, a platen carried on the lower end of said plunger, a solenoid surrounding said core and means for closing a circuit through said solenoid.
2. In a printing press, a base, standards extending up from said base, a transverse member connecting the upper ends of said standards, a plunger slidable through said transverse member and constituting a solenoid core, a platen carried on the lower end of said plunger, a solenoid surrounding said core, a fixed contact on the base, a lever pivoted on said base and carrying a movable contact movable into and out of engagement with the fixed contact, said lever having one end extending upward for engagement by paper inserted in said press, circuit wires including a source of electricity and connecting said contact with said solenoid, a spring normally holding said contacts open, springs connecting said platen and transverse members to normally hold the platen away from the base, and a cam member carried by the platen and engageable with the lever to open the connection between the contact upon the platen reaching printing position.

cluding a source of electricity and connecting said contact with said solenoid, a spring normally holding said contacts open, and springs connecting said platen and transverse members to normally hold the platen away from the base.

3. In a printing press, a base, standards extending up from said base, a transverse member connecting the upper ends of said standards, a plunger slidable through said transverse member and constituting a solenoid core, a platen carried on the lower end of said plunger, a solenoid surrounding said core, a fixed contact on the base, a lever pivoted on said base and carrying a movable contact movable into and out of engagement with the fixed contact, said lever having one end extending upward for engagement by paper inserted in said press, circuit wires including a source of electricity and connecting said contact with said solenoid, a spring normally holding said contacts open, springs connecting said platen and transverse members to normally hold the platen away from the base, and a cam member carried by the platen and engageable with the lever to open the connection between the contact upon the platen reaching printing position.

In testimony whereof I affix my signature.

JOHN B. BARNETT.
